UNITED STATES PATENT OFFICE.

ALBERT F. FIFIELD, OF NEWARK, NEW JERSEY, ASSIGNOR TO THE SINGER MANUFACTURING COMPANY, OF ELIZABETH, NEW JERSEY, A CORPORATION OF NEW JERSEY.

STITCH-FORMING MECHANISM FOR CHAIN-STITCH SEWING MACHINES.

1,421,488.

Specification of Letters Patent.

Patented July 4, 1922.

Application filed September 2, 1920. Serial No. 407,622.

To all whom it may concern:

Be it known that I, ALBERT F. FIFIELD, a citizen of the United States, residing at Newark, in the county of Essex and State 5 of New Jersey, have invented certain new and useful Improvements in Stitch-Forming Mechanisms for Chain-Stitch Sewing Machines, of which the following is a specification, reference being had therein to the accompanying drawings.

This invention relates to single chain-stitch sewing machines of the well-known rotary looper type disclosed, for example, in the United States patent to Willcox No. 15 44,490 of September 27, 1864.

In machines of this type, as commonly constructed, it is essential to the formation of enchain'd loops that the work be fed in the direction in which the looper-beak moves 20 when in loop-seizing position, in order that the descending needle may pass in front of both limbs of the previously formed loop held spread by the looper, whereby the looper-beak may first seize the nascent needle-loop and subsequently pass between the limbs of the previous needle-loop. These machines, therefore, while well adapted for straightaway sewing in the direction in which the looper-beak moves in seizing a 25 needle-loop, are practically inoperative when an attempt is made to sew while feeding the work in a direction opposite to the direction of movement of the looper-beak in seizing a needle-loop, the reason being that there is 30 no provision for insuring that the needle will descend in front of both limbs of the previously formed needle-loop and that the previous needle-loop will be held spread in a position such that the beak of the looper 35 will pass into it as is essential to the stitch-forming operation.

In utilizing chain-stitch mechanism of the rotary looper type in connection with a jogging work-holder such as is used in button 40 sewing or attaching price marks for example, in which, in forming some of the stitches, a component of movement is given to the work in a direction opposite to the direction in which the looper-beak moves in 45 seizing the needle-loop, it was found that by vibrating the looper-shaft laterally and making use of a loop-detaining spur or finger into engagement with which the limbs of the previous needle-loop were carried by 50 bodily jogging movements of the looper, the

said spur or finger being disposed at the opposite side of the needle-path from the loop-spreading portion of the looper-beak in its loop-seizing stage of movement, it 60 served to position the needle-thread loops uniformly regardless of the position of the last stitch. This mechanism is fully disclosed in my Patent No. 1,147,386 of July 20, 1915. 65

It has been found that under high speed operation the looper of the chain-stitch mechanism of said patent under certain conditions fails to enchain the needle-loops and it is evidently caused by a limb of the loop, 70 due to the high speed, whipping around the end of the loop-detaining spur or finger so that it is positioned to the front thereof and the limbs of the loop are therefore not held on the rear side of the needle-path as is necessary for a proper enchaining of the needle-loops. As the outer limb of the loop is shed around the outer edge of the heel portion of the looper-beak, it being stressed as it passes over this edge and then suddenly becoming 75 slack, the slack is sufficient to allow this limb to be carried around the end of the detaining spur or finger because of its momentum under high speed.

An object of the present invention is, 80 therefore, to improve the well known single chain-stitch mechanism of the rotary looper type so that it will enchain the needle-loops properly and with certainty when the work is given a component of movement in a direction opposite to the direction of movement of the looper-beak in its loop-seizing stage of movement.

Another object of the invention is to provide a sewing machine having stitch-forming mechanism of the rotary looper type adapted to form detached groups of fastening stitches in the formation of which relative jogging movements between the stitch-forming mechanism and work are employed 90 and some of these movements are in a direction opposite to the direction of movement of the beak of the looper when entering the loop to seize the same.

Still further the invention has for an object to prevent a limb of the needle-loop passing around the end of the loop-detaining spur or finger to the front thereof, so that it will be properly positioned by this spur or finger for entrance of the looper. 100 105 110

Further objects of the invention will appear from the following description and claims.

To attain these ends I have provided a looper of the rotary type with means for temporarily detaining the limb of the needle-loop after it has been shed or passed over the outer edge of the heel of the beak portion of the looper, until the slack has been taken up sufficiently by the loop-deflecting and spreading wing of the looper to prevent the limb passing or flipping over the free end of the loop-detaining spur or finger to the front thereof.

In the preferred construction this means comprises a pin set into the outer curved portion of the loop-deflecting and spreading wing of the looper at about the junction of this wing with the heel of the beak portion of the looper inwardly of the outer edge of this heel, and projecting a short distance from the surface of the looper at substantially right angles thereto.

Referring to the accompanying drawings, Fig. 1 is a front elevation of the free end of the machine bed or work-arm with a portion thereof broken away to disclose the looper, the work-holder being shown in elevation. Fig. 2 is a bottom plan view of the free end of the work-arm. Fig. 3 is a sectional elevation through the work-arm in a plane at about the free end of the looper showing the needle-loop in the position it occupies just before its outer limb is snapped over the edge of the heel of the looper-beak. Figs. 4 and 5 are end and side elevations, respectively, of the looper showing its relation to the needle and work, the looper being in the position occupied immediately after the outer limb of the thread-loop snaps over the heel of the looper-beak. Figs. 6 and 7 are views similar to Figs. 4 and 5 but showing the position of the thread-loop after the slack therein has been taken up by the loop-spreading and twisting portion of the looper, and Fig. 8 is a view similar to Figs. 4 and 6 showing the beak of the looper as about to pass a needle-loop through a previously formed loop.

In the particular embodiment of the invention illustrated the machine frame comprises a work-supporting arm 1 above which is the head 2 in which is journaled the reciprocating needle-bar 3 carrying the eye-pointed needle 4.

The present machine is provided with a work-clamp and operating mechanism therefor constructed substantially in accordance with the disclosure of my Patent No. 1,226,963 of May 22, 1917, and is adapted to handle either two or four-hole buttons. The work-clamp comprises the jogging bar 5 which extends longitudinally of and rests upon the work-arm 1. To the forward end of the bar 5 is secured the fabric supporting

plate 6 upon which rests the button-clamp comprising the opposed button-gripping jaws 7, 7 carried by the spring-pressed arm 8 secured upon a block (not shown) mounted upon the rearward end of the bar 5. Mechanism is provided for imparting longitudinal and transverse jogging movements to the work-clamp as clearly disclosed in my said Patent No. 1,226,963 and as this mechanism forms a part of the prior art and is not claimed specifically herein, further illustration and description thereof is believed to be unnecessary. It may be stated, however, that when the present machine is adjusted to sew four-hole buttons the work-holder is given movements having a component of movement in a direction opposite to the direction of movement of the looper-beak in its loop-seizing movement.

Journaled within and lengthwise of the work-arm 1 is a rotary looper-shaft into the enlarged and socketed end 9 of which is secured the shank of the rotary looper formed with a loop-seizing beak 10 and with the loop-deflecting, spreading and twisting wing 11. Between the heel 12 of the beak-forming portion of the looper and the wing 11 is a throat 13, the bottom of which affords a groove having forward and rearward extremities serving to spread the forward and rearward limbs *a*, *b*, respectively, of the needle-loop seized by the looper. Set into the looper on the opposite side from the throat 13 and at substantially the junction of the heel 12 of the beak-forming portion and the wing 11 is a pin 14 for a purpose presently to be described. This pin is rigid with the looper and extends outwardly a short distance from its surface at substantially right angles thereto. As shown in Figs. 5 and 7 it is located inwardly a short distance from the outer edge of the heel 12.

The end of the looper-shaft adjacent the looper is journaled in a block 15 slidably mounted in guideways 16 in the under side 110 of the work-arm so that during the operation of the stitch-forming mechanism the looper-shaft may be vibrated laterally.

Rigidly secured to the under side of the throat-plate 17 is a loop-detaining spur or finger 18 formed with a recess 19 on its rear side as shown in Fig. 2, in which at certain times the limbs of the needle-loop are detained after they are carried into engagement therewith by the bodily jogging movements of the looper and work-holder. The said spur or finger is disposed at the opposite side of the needle-path from the loop-spreading portion of the looper-beak in its loop-seizing stage of movement as shown in Fig. 8, and serves to position the limbs of the needle-thread loops uniformly regardless of the position of the last stitch. This mechanism is more fully disclosed in my Patent No. 1,147,386 of July 20, 1915.

It has been found, however, that when this mechanism is operated at high speed the looper sometimes fails to properly enchain the thread-loops or in other words the 5 machine skips stitches. As the needle-loop is seized and expanded by the beak 10 of the looper it is kept taut until the outer limb *a* is snapped over the outer edge of the heel 12 of the beak-forming portion of the looper 10 when, because of the peculiar shape of the looper, it immediately becomes slack, as shown in Figs. 4 and 5, and this slack is sufficient to allow the limb *a* of the loop to pass around the end of the detaining spur 15 or finger 18 to the front thereof or to the same side of this spur as is the needle-path, as shown in dotted lines *a'* in Fig. 4. Under high speed operation this sometimes happens when the limbs of the loop lead from 20 a point in the work to the front of the detaining spur or finger 18 or on the same side as the needle-path when the work as button B and fabric F is jogged to the right, as shown in Fig. 4, because the sudden 25 change from being taut to being slack as the limb *a* passes over the edge of the heel 12, together with its momentum carry it around the end of the spur or finger 18. It 30 will therefore be apparent that when this condition exists both limbs of the needle-loop are not held on the opposite side of 35 the needle-path from the looper-beak in its loop-seizing stage of movement and therefore it cannot carry the nascent loop through the previously formed loop and the loops are not enchainged.

However, when the pin or detaining means 14 is employed, as the limb *a* of the needle-loop is snapped around the edge of the heel 40 12 it is detained by said member 14 and held as shown in Figs. 4 to 7, until as the looper rotates the loop-spreading and twisting wing 11 has taken up sufficient slack to prevent the limb *a* from passing around 45 the end of the spur or finger 18 as shown in Figs. 6 and 7. At this time the rotation of the looper carries the member 14 out of the path of the limb *a* releasing the same so that the loop may be properly twisted 50 and positioned by the wing 11 and throat 13 for entrance of the next loop.

Although in my preferred construction the member 14 is a pin set into the looper so as to be rigid therewith as shown it obviously does not necessarily have to be of such construction, as the same operation and effect may be obtained by other structures, for example, by means of a lug formed integral with the looper.

It has been found that this simple expedient effectively prevents the mechanism as disclosed from skipping stitches under high speed.

Member 20 is an oscillating and bodily 65 movable needle-guard. It, however, forms

no part of my present invention and therefore it is not further described herein. Its function and operation is fully disclosed in my said Patent No. 1,147,386, above mentioned.

70

Mounted so that its free end bears lightly upon the surface of the looper is a flat spring or finger 21 forming a loop-controller to prevent a previously formed needle-loop flipping around over the beak of the looper 75 and thus causing a breaking of the loop. This device may or may not be employed with my present device. It is fully disclosed in my Patent No. 1,316,022 of September 16, 1919.

80

At the end of the stitching operation the thread-cutter 22 mounted on bellcrank-lever 23 pivoted to the throat-plate at 24 is operated to cut the thread by the stop-mechanism (not shown) through the draw-bar 25. 85 This mechanism, however, forms no part of the present invention and is substantially the structure disclosed in my Patent No. 1,251,451 dated December 25, 1917.

In the various figures the arrows indicate 90 the directions in which the parts are moving.

Having thus set forth the nature of the invention, what I claim herein is—

1. In a sewing machine, in combination, a reciprocating needle, a rotary looper having a loop-seizing beak and a loop-spreading wing, means adapted to position the loop at one side of the needle-path, and means on the looper to temporarily detain a limb of the loop after it has been passed 100 around the outer end of the looper.

95

2. In a sewing machine, in combination, a reciprocating needle, a rotary looper having a loop-seizing beak and a loop-spreading wing, means for detaining the loop at one 105 side of the needle-path, and means on the looper adapted to temporarily detain a limb of the loop after it has been passed over the outer end of the looper until the slack in the loop has been taken up by the action 110 of the loop-spreading wing of the looper.

3. In a sewing machine, in combination, a reciprocating needle, a rotary looper having a loop-seizing beak and a loop-spreading wing, a loop-detaining spur or finger 115 adapted to detain the loop at one side of the needle-path, and means to temporarily detain a limb of the loop after it has been passed around the outer end of the looper until the slack in the loop has been taken 120 up sufficiently to prevent its flipping around the end of the loop-detaining spur or finger.

4. In a sewing machine, in combination, a reciprocating needle, a rotary looper having a loop-seizing beak and a loop-spreading wing, a loop-detaining spur or finger having a free end and adapted to detain the loop at one side of the needle-path, and means to detain a limb of the loop after it has passed over the outer edge of the heel 130

of the looper-beak until the loop-spreading wing has taken up sufficient slack to prevent the loop passing around the free end of the loop-detaining spur or finger.

5. In a sewing machine, in combination with a reciprocating needle, a rotary looper shaft, a looper fixedly mounted on said shaft and formed with a loop-seizing beak and a loop-spreading wing, and means on the 10 looper for temporarily detaining a limb of the loop after it has been shed around the outer edge of the heel portion of the looper-beak.

6. In a sewing machine, in combination 15 with a reciprocating needle, a rotary looper having a loop-seizing beak and a loop-spreading wing, feeding means adapted to impart to the work a component of movement in a direction opposite to the direction 20 of the loop-seizing movement of the looper-beak, means to detain the loop at one side of the needle-path, and means on the looper for temporarily detaining a limb of the loop after it has been shed around the outer edge 25 of the heel of the looper-beak.

7. In a sewing machine, in combination, a reciprocating needle, a rotary looper having a loop-seizing beak and a loop-spreading and twisting portion, a thread-detaining 30 finger adapted to position the thread-loop at one side of the needle-path, and means on the looper adapted to detain one limb of the needle-loop after it has snapped over the heel of the looper-beak until the loop-spreading and twisting portion of the looper 35 has acted upon the opposite limb of the loop to take up the slack therein.

8. In a sewing machine, in combination, 40 a reciprocating needle, a rotary looper having a loop-seizing beak and a loop-spreading and twisting portion, a loop-detaining spur or finger adapted to position the thread-loop at one side of the needle-path, and means on the looper adapted to detain 45 a limb of the needle-loop in rear of the loop-detaining spur or finger until the loop-spreading and twisting portion of the looper has acted on the opposite limb of the loop to

take up sufficient slack to prevent the first limb passing around the end of the loop-detaining spur or finger to the front thereof. 50

9. In a sewing machine, in combination, a reciprocating needle, a rotary looper having a loop-seizing beak and a loop-spreading wing, means adapted to position the loop at 55 one side of the needle-path, and means on the looper for temporarily detaining a limb of the needle-loop after it has passed over the outer end of the looper comprising a projection extending outwardly from the surface of the looper at the back of the loop-spreading wing and at substantially the junction of this wing with the beak portion of the looper. 60

10. In a sewing machine, in combination, 65 a reciprocating needle, a rotary looper having a loop-seizing beak and a loop-spreading wing, means for positioning the loop at one side of the needle-path, and means in addition to said beak and wing for temporarily 70 detaining a limb of the loop after it has been passed over the outer end of the looper.

11. In a sewing machine, in combination with a reciprocating needle, a rotary looper having a loop-seizing beak and a loop-spreading wing, means for causing a relative movement between the work and the looper having a component in a direction opposite to the direction of the loop-seizing movement of the looper-beak, means to detain the loop at one side of the needle-path, and means for temporarily detaining a limb of the loop after it has been shed around the outer edge of the heel of the looper-beak. 75 80

12. In a sewing machine, in combination, 85 a reciprocating needle, a rotary looper having a loop-seizing beak and a loop-spreading wing, means for positioning the loop at one side of the needle-path, and means co-operating with the wing of the looper for 90 controlling the slack in the loop after it has passed around the outer end of the looper.

In testimony whereof, I have signed my name to this specification.

ALBERT F. FIFIELD.
